UNITED STATES PATENT OFFICE.

AZRO H. WAITE, OF EL PASO, ILLINOIS.

VAPOR-BURNER.

No. 861,066.

Specification of Letters Patent.

Patented July 23, 1907.

Application filed October 25, 1905. Serial No. 284,313.

To all whom it may concern:

Be it known that I, AZRO H. WAITE, a citizen of the United States, and a resident of El Paso, in the county of Woodford and State of Illinois, have invented a new and Improved Vapor-Burner, of which the following is a full, clear, and exact description.

The invention relates to burners using gasoline or like liquids as fuel, and its object is to provide a new and improved vapor burner arranged to quickly start the generation of the vapor without creating undesirable smoke, and to prevent the formation and escape of gas into the room after the burner is turned out, thus rendering the burner both smokeless and odorless.

The invention consists of novel features and parts and combinations of the same which will be more fully described hereinafter and then pointed out in the claims.

A practical embodiment of the invention is represented in the accompanying drawings forming a part of this specification, in which similar characters of reference indicate corresponding parts in all the views.

Figure 1 is a side elevation of the improvement; Fig. 2 is an enlarged sectional side elevation of the burner proper; Fig. 3 is a reduced plan view of the same; Fig. 4 is an enlarged sectional side elevation of the supply tank and its outlets; and Fig. 5 is a sectional plan view of the same, on the line 5—5 of Fig. 4.

In the detail description use is made of the terms evaporating burner and generating burner, the term evaporating burner signifying a burner in which the inflammable liquid drips onto a screen and is subjected to the action of air to evaporate the liquid and form with the air an inflammable gaseous mixture carried to the burner, no direct heat being used for vaporization. The term generating burner is used to designate a burner in which the vapor to be fed to the burner is formed by forcing gasoline or like liquid through a heated channel to vaporize the liquid previous to its entrance into the burner.

40 The improved vapor burner consists essentially of an evaporating burner A and a generating burner B arranged centrally relative to the evaporating burner A, both burners A and B receiving their supply of fuel from an overhead tank C, illustrated in Figs. 1, 45 4 and 5. The generating burner B supplies gas to auxiliary gas burners D, which may be used for any desired purpose.

The evaporating burner A consists of an annular closed mixing chamber A' (see Fig. 2) provided on the top with a perforated plate or screen A², through which passes the vapor to be burned on the top of the burner. Into one side of the mixing chamber A' and preferably near the lower end thereof, opens a gas supply pipe E having its upper end E' enlarged and containing an evaporator E², preferably in the form of a

tubular screen closed at the top and opening at its lower end into the gas supply pipe E. Into the enlarged end E' opens the upper end of a hot air supply pipe F connected, at its lower end, with a hot air collecting drum A³ surrounding the upper portion of the mixing chamber A', and closed at the top and open at the bottom for the admission of air. When the evaporating burner A is in use, air passes into the drum A³, and from the same, by way of the pipe F, into the enlarged end E' of the gas supply pipe E, so that the gasoline, which passes into the upper enlarged end E' comes in contact with the hot air and is thus vaporized and mixed with the air, and the mixture passes through the meshes of the evaporator E² into the latter, and finally into the pipe E and to the mixing chamber A' in which the vapor is mixed. The inflammable mixture thus produced is formed at the screen A², and the heat generated is utilized for heating, cooking vessels and the like, and also to heat the generating burner B surrounded by the flame produced by the evaporating burner A.

In order to control the liquid fuel passing into the upper end E' of the gas supply pipe E from the tank C, the following arrangement is made: The top of the upper end E' of the pipe E is provided with a spring-pressed socket G having a shell of glass or other transparent material and the said socket is engaged by a nozzle H containing a drip-valve I to allow the liquid fuel to flow in regulated quantities through the nozzle H and socket G into the upper end E', to be vaporized, as previously explained. The nozzle H is connected with the bottom of a chamber C' having its top connected by a valve opening C² with a chamber C³ connected at the bottom and top by openings C⁴ and C⁵ with the interior of the tank C, the said chambers C³ and C' forming integral parts of the tank C, and the chamber C' being provided with an air vent in the form of a pipe C⁶ extending to the top of the chamber C³. Within the chamber C' is arranged a valve J for controlling the valve openings C² and the valve J is held on a float J' adapted to rise and fall in the chamber C' with the liquid passing into the chamber C' by way of the valve opening C², chamber C³ and opening C⁴ from the tank C. Thus, when the liquid rises in the chamber C' the float J' rises correspondingly and the valve J cuts off the supply of liquid fuel, thus insuring an even pressure on the valve J whether the tank C is full or empty.

The generating burner B is preferably raised above the top of the evaporating burner and is provided with a base B' seated on the evaporating burner A and extending over the central opening thereof, and on the said base B' is centrally arranged a burner cap B² having the concentric chambers B³ and B⁴ provided with perforations in their side walls for the escape of

the generated gas to be burned outside of the cap B². The bottom chamber B⁴ is somewhat larger than the top chamber B³, which latter opens into the bottom chamber B⁴ and into the top chamber B³ opens the upper end of the supply pipe B⁵ extending centrally through the lower chamber B⁴. Into the lower end of the supply pipe B⁵ discharges a jet B⁶ controlled by a valve B⁷ arranged in the pipe B⁸ connected with an annular chamber B⁹ formed in the base B'. Into the 10 annular chamber B⁹ opens a stand pipe K connected with the bottom of the overhead tank C, so that gasoline or like liquid fuel can flow by gravity through the stand pipe K into the annular chamber B⁹, to be vaporized therein by the heat radiating from the evaporating burner A, as previously explained. The gas generated in the chamber B⁹ passes by way of the pipe B⁸ and jet B⁶ into the supply pipe B⁵, into which also enters atmospheric air from the bottom of the evaporating burner, so that a combustible mixture is produced which passes into the chambers B³ and B⁴ through the perforations thereof, to be burned on the outside of the cap B². The valve B⁷ is provided with a suitable handle B¹⁰ under the control of the operator for regulating the amount of vapor passing through the 15 jet opening B⁶. A branch pipe L extends from the chamber B⁹ to the auxiliary burners D to supply the same with gas from the said chamber B⁹.

In using the vapor burner, the evaporating burner A is first ignited, the valve B⁷ being closed, and the 30 amount of fuel to be supplied to the evaporating burner being regulated by the drip valve I. After the evaporating burner is in use for a while, the generating burner is heated to such an extent that it quickly generates gas within the chamber B⁹, so that when the 35 valve B⁷ is opened, the gas immediately passes under pressure out of the jet opening B⁶, to mix with the air to produce a combustible mixture, passing by way of the supply pipe B⁵ into the chambers B³ and B⁴ of the cap B², to be burned at the outside thereof as soon as 40 ignited by the surrounding flame of the evaporating burner A. As soon as the generating burner B is started the evaporating burner A may be shut off by the operator closing the drip valve I. If desired, however, both 45 burners A and B may be used simultaneously.

It is well known that in starting an ordinary generating burner, considerable smoke is produced; that is, until sufficient heat is obtained to form a proper combustible mixture; but as by my arrangement the generating burner B is highly heated before the valve B⁷ 50 is opened, it is evident that no smoke whatever can ensue, as the proper inflammable mixture immediately passes through the perforations of the chambers B³ and B⁴ to be burned on the outside of the cap B².

A serious fault of evaporating burners is that after the 55 supply of the liquid fuel is shut off, a further generation of gas still takes place, and this gas passes into the room and consequently an undesirable odor pervades the room. By my arrangement the evaporating burner A is preferably shut off soon after the generating burner B is started, and hence any gas that is generated in the 60 evaporating burner is burned by the flame of the gen-

erating burner B, and consequently no gas from the evaporating burner A escapes into the room.

From the foregoing it will be seen that the evaporating burner A overcomes a fault in the generating burner 65 B, and the latter rectifies the fault of the evaporating burner A, and consequently the burner is rendered completely smokeless and odorless.

Having thus described my invention, I claim as new and desire to secure by Letters Patent,— 70

1. A vapor burner, comprising an evaporating burner having a tubular open ended body and an annular mixing chamber surrounding the body and provided with a perforated top, and a generating burner having an annular marginal generating chamber and a centrally arranged burner cap projecting above the chamber, the generating burner being seated upon one end of the body of the evaporating burner with its generating chamber adjacent to and rising above the perforated top of the mixing chamber of the 75 evaporating burner.

2. A vapor burner, comprising an evaporating burner having a tubular and open ended body and an annular mixing chamber surrounding the body and having its top covered by a screen, and a generating burner provided with a base having an annular marginal generating chamber rising 85 therefrom and with a centrally arranged burner cap projecting above the chamber, the generating burner having its base seated on one end of the body of the evaporating burner with a portion thereof extending into said body, the generating chamber thereof being adjacent to and projecting above the screen covered top of the mixing chamber of the evaporating burner.

3. In a vapor burner, an open ended shell having an annular mixing chamber surrounding it, said mixing chamber having its top covered by a screen, means for admitting 95 carbureted air into the mixing chamber, a burner having an annular marginal generating chamber and a centrally arranged burner cap, said burner being seated on the upper end of the shell over the opening thereof, and means within the shell for admitting the gas generated in the generating chamber of the burner to said burner.

4. In a vapor burner, an open ended shell having an annular mixing chamber surrounding it, said chamber having its top covered by a screen, an evaporator connected with said chamber, a burner having an annular marginal 105 generating chamber, a centrally arranged burner cap and a central supply pipe, the said burner being seated upon the shell over the opening thereof with its supply pipe extending into the shell, and a pipe within the shell and leading from the generating chamber to a point below the 110 supply pipe of the burner and provided with a discharge jet.

5. A vapor burner, comprising an evaporating burner having an open ended tubular body and an annular mixing chamber surrounding the body, said mixing chamber being 115 provided with a perforated top and with the lower portion of which the evaporator of the said burner is connected, and a generating burner comprising a base seated upon upper end of the tubular body of the evaporating burner and having an annular chamber, superimposed perforated 120 chambers, a central supply pipe extending from the upper chamber through the lower one into the body of the evaporating burner, a pipe leading from the said annular chamber down into the body of the evaporating burner and provided with a discharge jet below the supply pipe, and a 125 valve for said jet, said valve having its handle below the lower end of the body of the evaporating burner.

In testimony whereof I have signed my name to this specification in the presence of two subscribing witnesses.
